UNITED STATES PATENT OFFICE.

WILLIAM MACDONALD AND WILLIAM MACD. VEALE, OF PHILADELPHIA, PENNSYLVANIA.

PORTABLE STREET OR ROAD CAROUSEL.

SPECIFICATION forming part of Letters Patent No. 773,292, dated October 25, 1904.

Application filed July 10, 1903. Serial No. 164,930. (No model.)

To all whom it may concern:

Be it known that we, WILLIAM MACDONALD and WILLIAM MACD. VEALE, citizens of the United States, residing at Philadelphia, in the county of Philadelphia and State of Pennsylvania, have invented certain new and useful Improvements in Portable Street or Road Carousels, of which the following is a specification.

10 This invention relates to an amusement device of the carousel or merry-go-round order, and is designed and constructed for portability in order to be operated in streets and roads for the amusement of small children 15 near their homes in similar manner of street pianos and organs. While it is illustrated as arranged for transportation by manual power, it can very readily be arranged to attach a horse, and means are provided to turn a hand- 20 organ or any musical instrument similarly operated while carousel is operated.

The accompanying drawings illustrate the invention, wherein like characters of reference indicate like parts, and in which— 25 Figure 1 is a top or plan view. Fig. 2 is a side elevation. Fig. 3 is a plan of the central antifriction-bearing. Fig. 4 is a section on line $\alpha\alpha$, Fig. 3.

30 A platform 1 is mounted on a pair of rear wheels 2 and a pair of front wheels 3, which are pivotally attached to the platform at 4, and axle 5 has thills 6 thereto attached, by which the machine is drawn and guided. Secured to the top of platform 1 is a grooved 35 ring 7, above which is another grooved ring, 8, and between the rings in their respective grooves 9 10 are a series of balls 11, designed to travel in the grooves. Ring 8 has a series of pockets 12, in which are inserted and se- 40 cured the inner ends of a series of radial sills 13, on which the floor 14 of the carousel is placed and which also support the outer inclosure 15. The inclosure is shown as of close or solid material, and it may be of any ma- 45 terial which will afford absolute safety and of solid, open, or net work construction.

Passing through the center of rings 7 8 and through platform 1 and floor 14 is a center-pin 16, having a head 17 resting on a plate

18 on sills 13, the pin having a key 19 to secure it to ring 8. Below platform 1 a bevel-gear 20 is secured to center-pin 16 by a key 21, so that as the gear is rotated the ring 8 and the inclosure 15 will also rotate. Engaging gear 20 is a gear 22 on a shaft 23, supported in bearings 24 25. At the outer end of shaft 23 a spur-pinion 26 is secured, and it is engaged and rotated by a gear 27, having a crank-handle 28, by which it is turned. The gear is supported on a pin 29, secured in an 60 upright 30, which is attached to platform 1. A shield 31 is placed over gear 27 to protect the accidental touching of the gear or its teeth.

As the stopping-place may frequently be on an unlevel surface, means are provided for 65 leveling the platform by a telescopic rod 32, passing into a seat 33, secured under bearing 25 and having an adjusting-screw and hand-wheel 34. In heavy machines this may need to be modified or have additional means to 70 elevate the platform.

Inclosure 15 is provided with seats 35, shown 75 radially disposed, so the children can face in the direction of rotation; but it will be evident that a continuous circular seat or animal-models might be preferable in some localities and used to equal advantage. Inclosure 15 has a door or gate 36 opening to the rear end of platform 1 for ingress and egress, and the platform is provided with steps 37 80 and hand-rails 38.

As it is proposed to operate these machines on a royalty, they will be provided with a turnstile 39 of any of the well-known suitable constructions which record when the 85 arms 40 are moved in the direction of the solid-line arrow and do not record when they move in the opposite direction, as shown by the broken-line arrow.

Inclosure 15 may be provided with a canopy 90 or staffs for flags or pennants.

For the purpose of playing an organ or musical instrument shaft 23 may be extended beyond gear 20 and be provided with a pulley 41 or other suitable means for such purpose, or center-pin 16 may instead of shaft 23 be extended for the same purpose.

In large machines where proper facilities

exist an electric or similar safe motor may be employed for rotation instead of crank-handle 28 and manual power.

We claim—

- 5 A portable carousel comprising a wagon having a platform and a rotary inclosure pivotally mounted upon said platform; steps on the platform and a hand-rail to the steps; a door in the inclosure or revolving part of the
- 10 carousel adapted to communicate with the steps; and means mounted upon the platform

and connected with the inclosure, and independent of the running-gear, for rotating the inclosure when the wagon is at rest.

In testimony whereof we affix our signatures 15 in presence of two witnesses.

WILLIAM MACDONALD.
WILLIAM MACD. VEALE.
